OP   n   14,352

Design No. 14,352, dated October 23, 1883.

UNITED STATES PATENT OFFICE.

RUDOLPH BARTEL, OF JERSEY CITY, NEW JERSEY.

DESIGN FOR A GLOVE.

SPECIFICATION forming part of Design No. 14,352, dated October 23, 1863.

Application filed August 5, 1883. Term of patent 7 years.

To all whom it may concern:

Be it known that I, RUDOLPH BARTEL, a citizen of the United States, residing at Jersey City, in the county of Hudson and State of New Jersey, have invented and produced a new and original Design for Gloves, of which the following is a specification.

This design is especially adapted to ladies' or children's gloves; and it consists of gussets or gores of lanceolate shape and puffed or ruffled, arranged on the wrist portion of such articles.

The accompanying photograph shows a glove containing my design.

In this photograph, the letter A designates the body of the glove, and B a series of gussets or gores on the wrist portion thereof. These gussets or gores are of elliptic lanceo-

late shape or outline, and are puffed or ruffled, thus imparting to the glove what may be termed a "mediaeval" appearance. 20

What I claim as new, and desire to secure by Letters Patent, is--

The within-described design, consisting of a glove having its wrist portion provided with puffed or ruffled lanceolate shaped gussets or 25 gores B, as shown.

In testimony whereof I have hereunto set my hand and seal in the presence of two subscribing witnesses.

RUDOLPH BARTEL. { U. S. }

Witnesses:

E. F. KASTENHUBER,
J. HERMANN WAHLERS.
